DESIGN FOR A COMBINATION MONEY CLIP AND WATCH

James Leslie Younghusband, Chicago, Ill.

Application April 20, 1945, Serial No. 119,110

Term of patent 14 years

(Cl. D42—7)

To all whom it may concern:

Be it known that I, James Leslie Younghusband, a citizen of the Dominion of Canada, residing at 30 West Hubbard Street, Chicago, Illinois, have invented a new, original, and ornamental Design for a Combination Money Clip and Watch, of which the following is a specification, reference being made to the accompanying drawing, forming a part thereof.

Referring now to the drawing, Fig. 1 is a front view of a design embodying my combination money clip and watch; Fig. 2 is a rear view, and Fig. 3 is a side elevational view of the same.

I claim:

The ornamental design for a combination money clip and watch, substantially as shown.

JAMES LESLIE YOUNGHUSBAND.
